UNITED STATES PATENT OFFICE.

JOHN H. DEAN, OF GRAND RAPIDS, MICHIGAN.

CIGAR-PACKING MACHINE.

Application filed January 17, 1921, Serial No. 437,658. Renewed October 13, 1924.

To all whom it may concern:

Be it known that I, JOHN H. DEAN, a citizen of the United States of America, residing at Grand Rapids, in the county of Kent and State of Michigan, have invented certain new and useful Improvements in Cigar-Packing Machines; and I do hereby declare the following to be a full, clear, and exact description of the invention, such as will enable others skilled in the art to which it appertains to make and use the same.

This invention relates to cigar packing machines and is particularly concerned with a machine of this character in which a quantity of cigars may be placed and the same compressed for entrance into boxes or other containers therefor. The invention consists of many novel constructions and arrangements of parts for effectively attaining this end, and for compressing the cigars either to enter a box of rectangular outline or a can of circular cross section. Various other objects and purposes of the invention will appear as understanding of the invention is had from the following description, taken in connection with the accompanying drawings, in which,

Fig. 1 is a front elevation of the cigar packing machine, the same having means for compressing cigars for entrance into cylindrical containers.

Fig. 2 is a plan view thereof.

Fig. 3 is a vertical transverse section taken on the plane of line 3--3, of Fig. 2.

Fig. 4 is a fragmentary rear elevation of the machine.

Fig. 5 is a view similar to Fig. 1 of a modified form of construction and showing the same compressing cigars for entrance into the usual cigar boxes, and

Fig. 6 is a fragmentary front elevation of the machine shown in Fig. 5, modified for the compressing of cigars for entrance into cylindrical containers.

Like reference characters refer to like parts in the different views of the drawings.

In the construction of the cigar packing machine, a base 1 of rectangular shape is used at the rear edge of which a vertical back 2 is secured, the same being longitudinally slotted at one end for a distance as indicated at 3. A vertical end 4 is secured to base 1 and back 2 at the opposite end of the back.

A vertically positioned member 5 is movably mounted on and above the base and in

front of the back, paralleling the end 4 and mounted for movement toward and away from said end. A rod 6 extends horizontally from member 5 on which a sleeve 7 is loosely secured, this sleeve being formed at the front part of a post 8 which is adjustably secured to the back 2, a reduced portion of the post extending through slot 3 and having a nut 9 threaded thereon, tightening of which secures the post in rigid relation to the back and loosening of which frees it for adjustment lengthwise of the back. A horizontal stop rod 10 passes through post 8 and is adapted to be secured in any position to which it is adjusted by a set screw 11.

A handle 12 is pivotally mounted at 13 at the front end of post 8. A link 14 pivotally connected to the handle at 15 at one end is pivotally connected at its other end at 16 to ears 17 projecting from a metal plate 19 secured to the outer side of member 5, the end of rod 6 also being secured to plate 19. The intermediate portion of the plate 19 at its lower edge is cut away leaving downwardly projecting ears at each end between which a roller 18 is mounted, the same riding against the upper side of base 1. By operating handle 12, the member 5 may be moved back and forth with respect to the end 4, as is evident, rod 10 limiting the outward movement of the member 5, and rod 6 sliding through sleeve 7 serving to hold the member in upright position. A sheet metal auxiliary back 2a is connected with the post 8 and may be adjusted therewith, serving to cover the slot 3 as shown.

A flexible apron 20 is extended between the upper edges of the end 4 and the member 5, being secured at one end to member 5 by a clamping bar 21 and at the other end to the end 4 by a clamping bar 22. The bars may be attached by screws which may be loosened for adjusting the apron as desired.

A casting 23 is permanently secured to the rear side of back 2 and has two upwardly extending arms 24 between which at their upper ends a rod 25 is held. A bar 26 is slidably mounted on the rod between its ends and is positioned vertically, the lower end of the bar passing between the back 2 and an outwardly projecting guide portion 27 cast with the member 23. The upper end of bar 26 is turned forwardly and a vertical rod 28 is secured between the same and a forwardly projecting ledge on

the bar as shown in Fig. 3. An arm is adjustably mounted on rod 28, said arm, indicated at 29 extending forwardly and being adjustably secured on the rod by a set screw 30. A vertically positioned rod 31 depends from the front end of the arm 29, passing freely at its upper end through a sleeve formed on the arm. A head 32 having a concaved under side is connected to the lower end of rod 31.

A handle 33 is pivotally mounted at one end on a projecting stud 29^a formed integral with arm 29 and link 34, similar to link 14, heretofore described is pivotally connected at its upper and lower ends to the handle and the head, respectively, at 35 and 36, the head being formed with two upwardly extending ears 37 between which the lower end of the link passes and to which it is connected. The downward movement of the handle is limited by a stop lug 38 on the handle engaging against the link as shown in Fig. 4.

With a construction of the character described, a bundle of cigars, as indicated at 39 may be placed on the apron 20, being preferably placed within overlapping pieces 20^a of celluloid or equivalent flexible material, after which the handle 33 is operated downwardly to bring head 32 against the bundle thereby compressing them into smaller space so that the same may be inserted into the open end of a cylindrical container 39^a. The celluloid members serve as guides for the entrance of the bundle of cigars into the container, being removed after the cigars are well in the container. The member 5 moves automatically with the downward pressure of the head on the cigars and permits the apron to conform to the under side of the bundle whereby the bundle is compressed into substantially cylindrical shape. The roller 18 permits the free movement of member 5 back and forth and the automatic inward movement of said member under pressure on the cigars from above. The head 32 having under concaved surface aids in compressing the bundle to substantially cylindrical form so that it may be conveniently entered into the cylindrical container. For different sizes of bundles, the apron may be adjusted to greater or less effective lengths and different sizes of heads 32 may be used and centered over the cigar bundles by moving the head and associated parts along rod 25. The member 5 may be moved outwardly whenever desired by operating handle 12, and in the same manner head 32 may be elevated by lifting handle 33.

This construction is relatively simple and yet particularly effective for the work to be done. The same construction may be used for compressing cigars in packages for entrance into cigar boxes as indicated in Fig. 65, a flat pressure board 40 being secured to

a head 41 which is operated by the handle 33 the same as head 32 is operated. In this case, the member 5 is moved manually against the end of the pack of cigars by operating handle 12, whereas with cylindrical packages of cigars supported on apron 20, the end 5 is moved inwardly automatically as needed. It will be noted that the centers of the pivots at 15 and 35 move beyond the line joining the centers of pivots 13 and 16 in the one case and the centers of pivots 29^a and 36 in the other, thereby causing the levers 12 and 33 to lock against return while the pressure is on the cigars, and maintaining the cigars in compressed position without necessitating the maintenance of force on the levers or handles 12 and 33.

I have shown and described a practical and operative construction fully capable of use in compressing both cylindrical packages of cigars and rectangular packages, of any and all sizes desired. The machine is universal in use and is particularly effective. The claims define the invention and I consider myself entitled to all forms of structure coming within their scope.

I claim:

1. In combination, a supporting base, a back attached to and extending upwardly from said base, an end member located at one end of the base and back and extending in front of the back, a member parallel to the end member movably mounted on the base, a flexible apron attached at its ends to said member and end member and extending between the same, a head movably mounted above the apron, and means for forcing said head downwardly against articles placed on the apron to compress the same, said member moving automatically inward and toward the end, substantially as and for the purposes described.

2. In combination, a base, a back attached to and extending upwardly from the base, an end member located at one end of the base and back and extending in front of the back, a member parallel to the end member, means for movably mounting said member to move toward or away from said end, a flexible apron disposed between said member and end member, a head having a concaved under side movably mounted above the apron, and means for forcing the head toward the apron and against articles placed on the same to compress them into a cylindrical package, substantially as described.

3. In combination, a base, a back attached to and extending upwardly from the rear part of the base, an end member located at one end of the base and back and extending in front of the back, a member parallel to said end member, a roller at the lower end of said member riding on the base, means for moving said member back and forth on the base, a head located above the end member

and said member and between the same, and means for forcing said head downwardly toward the base, substantially as described.

4. In combination, a base, a back attached to and extending upwardly from the rear part of the base, an end member located at one end of the base and back and extending forwardly from the back, a member paralleling said end member and movably mounted above the base for movement toward or away from the end member, a flexible apron disposed between the upper edges of the end member and said member, means for adjustably connecting the apron at its ends to said end member and member, a head having a concaved under side movably mounted above the apron, and means for forcing the head downwardly against articles placed on the apron to compress the same into a substantially cylindrical package, substantially as and for the purposes described.

5. In combination, a base, a vertical back attached to the base, a vertical end member located at one end of the base and back, a member movably mounted on the base and back and positioned in substantially parallel relation to said end member, an apron extending between said end member and second member and passing over the upper edges thereof, a clamping bar attached to each the end member and second member and under which the ends of the apron are secured, a head having a concaved under side mounted over the apron, and means for forcing said head in a downward direction against articles placed on the apron to thereby compress the same into a substantially cylindrical package, substantially as described.

6. In combination, a flexible support for packages of cigars, means for holding said support at one end against movement, movable means to which the opposite end of the flexible support is secured, a head having a concaved under side movably mounted over the flexible support, and means for forcing said head in a downward direction against said cigars placed on the flexible support to compress the same into substantially cylindrical form for insertion into a cylindrical container.

7. In combination, a relatively fixed ver-

tical support, a second support paralleling the first support and movably mounted to move toward or away from the first support, a flexible apron disposed between the upper ends of said supports, a head having a concaved under side movably mounted above the apron, and means for forcing the head downwardly against articles placed on the apron, substantially as and for the purposes described.

8. In combination, a relatively fixed vertical support, a second support paralleling the first support and movably mounted to move toward or away from the first support, a base to which the first support is connected and over which the second support moves, a head mounted above the base for movements toward or away from the base between the supports, means for forcing the head downwardly and against articles held on the base between the supports, said means including devices for preventing return of the head after it has passed a predetermined position, and similar means for moving the movable support toward the fixed support and preventing its return after it has passed a predetermined position, substantially as described.

9. In combination, a base, a relatively fixed vertical support thereon, a second vertical support mounted for movements toward or away from the vertical first support, a head movably mounted above the base between the supports, a pivotally mounted handle for the head and a similar handle for the movable support, a link pivotally connected to the head at one end and to the first handle at the other end a distance from the pivot of the handle, the pivot of the link on the handle passing across the line of centers of the handle pivot and the pivot of the link on the head in its movements, and a similar link similarly connected to the second handle and the movable support, whereby after the pivots of said links to the handles have passed said center lines for pressing the head and vertical movable support against articles located on the base between the vertical supports return movement is prevented, substantially as described.

In testimony whereof I affix my signature.
JOHN H. DEAN.
